UNITED STATES PATENT OFFICE

2,494,522

SHEET METAL REEL

Frederick R. Schaefer, Youngstown, Ohio, assignor to Republic Steel Corporation, Cleveland, Ohio, a corporation of New Jersey

Application July 13, 1946, Serial No. 683,479

5 Claims. (Cl. 242—123)

1
This invention relates generally to the metal reel art and is particularly concerned with a reel having new end construction including provision for the application of a braking or driving belt thereto.

Sheet metal reels, as constructed heretofore, have possessed several disadvantages. The ends or heads were not sufficiently strong and rigid even when welded or riveted constructions were used, especially when the reel was heavily loaded, and no satisfactory way was known for embodying in sheet metal reels means to control the rate of rotation of the reel when it was being unloaded.

By means of the present invention I have overcome these disadvantages. I have made sheet metal reels which are quite substantial, particularly as regards the strength and rigidity of the ends, by making reel ends from sheet metal parts which are connected by double seams at their outer peripheries and mutually brace each other. This construction makes it possible to incorporate in the peripheries of the ends belt grooves for use in controlling the rate of rotation of the reel.

In the drawings which accompany and form a part of this specification and which show various forms of the invention,

Figure 1 is an end view of one form of reel embodying the present invention.

Figure 2 is a fragmentary, central, sectional view taken on line 2—2 of Fig. 1.

Figure 3 is a fragmentary end view of a modified form of the present invention.

Figure 4 is a fragmentary, central, sectional view taken on line 4—4 of Fig. 3 corresponding to Fig. 2.

Figures 5 and 6 are, respectively, fragmentary end and top plan views of means for securing lagging in place on the reel of Figs. 3 and 4, Fig. 5 being taken on line 5—5 of Fig. 6.

Figure 7 is a fragmentary, sectional view showing one form of construction of the outer edges of the ends of a sheet metal reel.

Figure 8 is a view similar to Fig. 7 but showing a modified form of construction.

Figure 9 is a fragmentary, end elevational view of a modified form of the present invention.

Figure 10 is a sectional view taken on line 10—10 of Fig. 9; and

Figure 11 is an enlarged, fragmentary, sectional view of a rim structure slightly different from that shown in Figs. 9 and 10.

The reel shown in Figs. 1 and 2 comprises an elongated, cylindrical sheet metal hub 1 having inturned flanges 2 at each end and shoulders 3 near each end. The ends or heads of the reel of

5 Figs. 1 and 2 are alike and, accordingly, a description of one will suffice for both. Each end or head includes a ring 4 having out-turned flanges 5 and 6 at its inner and outer edges, respectively. The inner flange rests on the outside of hub 1 and abuts against shoulder 3 and is preferably welded to hub 1. Each end or head also includes a disk 7 of sheet metal which has an opening 8 at its center and one or more openings 9 which open into the interior of the hub. The disk 7 rests on inturned flanges 2 of hub 1 and are preferably welded thereto. Disk 7 is inclined toward ring 4, as is indicated at 10, and at its outer edge has a double seam connection 11 with flange 6 of ring 4. The openings 8 in the ends of the reel are to receive an axle on which the reel may rotate during loading and unloading and openings 9 may be used to engage pins on a head which is employed to rotate or drive the reel during loading.

20 The reel of Figs. 3 and 4 is quite like that of Figs. 1 and 2, and like numerals indicating like parts in these several figures. The end disks 7a are quite like disks 7 of Figs. 1 and 2 but differ 25 therefrom in certain respects. The flanges defining openings 8 and 9 are reinforced by rings 12 which are disposed on the inner side of each disk 7a, surround the disks of these openings and are welded to the disk. The outer portions 10a of disks 7a are deformed at a plurality of places, as indicated at 13, to bear against ring 4 and thereby add to the strength and rigidity of the head end. A double seam 11 joins the outer periphery of disk 7a to the outer flanges 6 of ring 4.

25 Lagging is shown in Figs. 3 and 4. A plurality of metal sheets 15 are provided with channel shaped edges 16 to seat on the ends of the reel and cover the material which is wound on the hub. As is better shown in Figs. 5 and 6, the adjacent ends of sheets 15 are bent back to form hooks 17 over which a clip 18 is fitted to retain the ends in position. One end of each clip 18 is bent over and bears on the outer side of the reel head and are attached, preferably by welding 19, to a partly 30 cut away portion 20 of disk 7a. Each clip 18 has a hole 21 near one end thereof and parallel scoring 22 extending from said opening to a corresponding hole at the other end. The partly cut away portion 20 and scoring 22 facilitate removal of the lagging.

35 In Fig. 7 is illustrated a modified form of construction of the outer periphery of the reel or heads. In this case the ring 4' has a flange 6a which extends axially, then outwardly as at 6b, and then is folded back into V-shape as is shown

at 6c. Disk 7' is shaped to conform to portions 6a, 6b and 6c of the flange of ring 4' and has a portion 7b which extends inwardly radially and flange 7c which rests on the outer side of flange 6a of ring 4'. These engaging parts of ring 4' and disk 7' form a V-shaped groove 25 for receiving a driving or braking belt to control rotation of the reel during unloading, and also during loading, if desired.

Fig. 8 shows a grooved end or head construction somewhat like that shown in Fig. 7. In this instance, however, the outer flange 6' of ring 4'' is bent to form one side on the bottom of a groove 28, the other side thereof being formed by the double seam connection 16' of flange 6' of ring 4' and flange 11' of disk 7'.

It will be understood that the end disks of Figs. 1 and 2 may be reinforced as is shown in Figs. 3 and 4 and may be provided with lagging and lagging securing means as shown in those two figures. It will also be understood that the ends or heads of the reels of Figs. 1 to 4 may be provided with grooves as shown in Fig. 7 or 8 or obvious variations thereof.

In Figs. 9 and 10 the illustrated reel comprises a sheet metal drum 31 and an end or head composed of ring 32 and disk 33. Ring 32 has a flange 34 which projects inwardly between the end of the hub 31 and disk 33. Ring 32 extends along the outer surface of hub 31 as is indicated at 35 and then extends outwardly at right angles to the drum as at 36. Disk 33 is spaced axially from ring 32 except for engagement with flange 34 and for the circumferentially spaced engagements indicated at 37 where the disk is depressed sufficiently to contact with the ring. The outer peripheries of ring 32 and disk 33 are double seamed together to form a rim 38 having a belt receiving recess 39. As is indicated by dotted lines 40 of Fig. 9 a stiffener 41 is fastened to the inner surface of disk 33 about openings 42 and 43 which extend thru the disk.

Figure 11 shows a double seam construction slightly different from that shown in Figure 10. The ring 32' and the disk 33' are bent the same as in Fig. 10 but the folds of metal at the periphery are not flattened down onto one another as in Fig. 10 but, on the contrary, are separated to provide space 45.

Reel ends or heads embodying the present invention are exceptionally strong and rigid as will be seen from examination of the forms illustrated in the drawings. The disk and ring comprising a reel head are connected to each other at their outer peripheries and to the hub at their inner peripheries. The outer connections are double seams, that is, the edge portions of the disk and ring are folded or rolled upon themselves to form an interlocked joint which is strong and which is lighter and less expensive than welded or riveted connections. The disk and ring are inclined to each other and thereby cooperate to resist side thrusts and may constitute an even more rigid structure when the disk is deformed to engage the ring at spaced places at 43 in Figs. 3 and 4. Moreover, these advantages may be realized in reels having belt grooves around the heads and having lagging to protect the article wound upon the hub. Thus the present invention satisfies long felt needs in reels and provides efficient, light and inexpensive apparatus.

Having thus described my invention so that others skilled in the art may be able to understand and practice the same, I state that what

I desire to secure by Letters Patent is defined in what is claimed.

What is claimed is:

1. A heavy-duty, light-weight, sheet metal reel comprising a hub and ends, said hub including an elongated sheet metal cylinder, said ends each including a sheet metal ring seating on and secured to said hub near an end thereof and a sheet metal disk secured to the end of the hub, the outer portions of said ring and disk extending axially and transversely of the reel and being folded upon themselves to form a rim having at least four interlocked, concentrically arranged layers of sheet metal, the ring and disk being spaced apart from each other at the hub and being out of continuous circumferential contact with each other between the hub and the rim.

2. A heavy-duty, light-weight, sheet metal reel comprising a hub and ends, said hub including an elongated sheet metal cylinder, said ends each including a sheet metal ring seating on and secured to said hub near an end thereof and a sheet metal disk secured to the end of the hub, the outer portions of said ring and disk extending axially and transversely of the reel and being folded upon themselves to form a rim having at least four interlocked, concentrically arranged layers of sheet metal, the ring and disk being spaced apart from each other at the hub and being out of continuous circumferential contact with each other between the hub and the rim, with one of said layers being bent to form a belt groove.

3. A heavy-duty, light-weight, sheet metal reel comprising a hub and ends, said hub including an elongated sheet metal cylinder, said ends each including a sheet metal ring having a flange seated on, and secured to, said hub and extending axially toward the end of the hub and a sheet metal disk secured to the end of the hub, the outer portions of said ring and disk being secured together to form a rim by being extended axially and transversely of the reel and being folded upon themselves to form at least four interlocked concentrically arranged layers of sheet metal, said ring and disk being out of circumferentially continuous contact with each other from the hub to the rim.

4. A heavy-duty, light-weight, sheet metal reel comprising a hub and ends, said hub including an elongated sheet metal cylinder, said ends each including a sheet metal ring seating on and secured to said hub near an end thereof and a sheet metal disk having side surface engagement with the end of the hub and secured thereto, the outer portions of said ring and disk being secured together to form a rim by being extended axially and transversely of the reel and being folded upon themselves to form at least four interlocked concentrically arranged layers of sheet metal, said ring and disk being out of continuous circumferential contact with each other between the hub and the rim.

5. A heavy-duty, light-weight, sheet metal reel comprising a hub and ends, said hub including an elongated sheet metal cylinder, said ends each including a sheet metal ring having a flange seated on and secured to said hub near an end thereof and extending axially toward the adjacent end of the hub and a sheet metal disk having side surface engagement with the end of the hub and secured thereto, the outer portions of said ring and disk being secured together to form a rim by being extended axially and transversely of the reel and being folded upon themselves to form at least four, interlocked, con-

centrically arranged layers of sheet metal with one of said layers being bent to form a belt groove, said ring and disk being out of continuous circumferential contact with each other between the hub and the rim.
